UNITED STATES PATENT OFFICE.

JOSEPH KADIERA, OF CHICAGO, ILLINOIS, ASSIGNOR OF ONE-HALF TO T. J. HRUBY, OF CHICAGO, ILLINOIS.

TURBINE.

No. 895,027.

Specification of Letters Patent.

Patented Aug. 4, 1908.

Application filed January 11, 1908. Serial No. 410,378.

To all whom it may concern:

Be it known that I, JOSEPH KADIERA, a subject of the Emperor of Austria-Hungary, residing at Chicago, in the county of Cook 5 and State of Illinois, have invented a new and useful Improvement in Turbine-Engines, of which the following is a specification.

My invention relates, more particularly, to the type of engines employing a rotary piston or turbine wheel provided with a plurality of impact-surfaces against which the motive fluid is directed; and my primary object is to improve the effectiveness of engines of this type by using the power of the 15 motive fluid for driving the engine to the greatest advantage.

A further object is to provide an engine which will develop high speed and great power when driven in both forward and reverse directions.

Referring to the accompanying drawings—Figure 1 is a view in vertical sectional elevation of an engine constructed in accordance with my invention. Fig. 2 is a section taken 25 at the line 2 on Fig. 1 and viewed in the direction of the arrow. Fig. 3 is a view in side elevation of one side of the inner casing of the engine showing the mechanism for operating its fluid-pressure valves; Fig. 4 is a similar 30 view of the opposite side of the inner casing showing the location of the pipes through which the fluid-pressure is supplied to the inner casing; and Fig. 5 is a broken section taken at the line 5 on Fig. 1 and viewed in 35 the direction of the arrow, the rotary member of the engine being removed in this view.

The outer shell or casing of the engine, which is shown to be of general cylindrical form, is represented at 6, and is formed to 40 provide a tubular extension 7 on its lower end which communicates with a pipe 8 fixed in a standard 9 and through which the spent fluid exhausts as hereinafter described. One side of the casing is open and is adapted 45 to be closed by a cover-plate 10 secured thereto as by bolts 11.

Secured to the cover-plate 10, as by screws 12, is an inner cylindrical casing 13 provided on its upper and lower portion with ribs 14, 50 14. The casing 13, which contains diametrically opposed openings 15, 15 in its cylindrical wall, is spaced throughout the greater portion of its circumference from the inner circumference of the outer casing to afford 55 outlet passages 16, 16 communicating with

the openings 15 and with a passage 7^a provided in the extension 7. The rotary member or turbine-wheel of the engine is represented at 17, and as shown is of hollow form with stub-axles 18, 18 extending from its 60 sides in opposed directions for journaling the wheel in the sides of the inner and outer casings, one end of the shaft extending beyond the outer casing, as represented, for receiving any suitable power transmission device 65 (not shown), for transmitting the power generated by the wheel for any desired purpose.

The sides of the wheel 17 are so proportioned relative to the sides of the casing as to permit the wheel to readily revolve therein 70 without permitting undue escape of motive fluid. The periphery of the wheel 17 between the circumferential margins of its sides is transversely grooved to form a succession of abutments or fluid impact-surfaces, the forms and arrangement of which are preferably as represented in Fig. 1, the following being a description thereof: A series of grooves 19 of arc shape in cross-section and preferably of uneven number, each 75 forming an impact-surface 20 and 21, and each of said grooves separated from the other by a pair of oppositely extending grooves 22 and 23, walls of which undercut the rim of the wheel in which the adjacent 80 grooves 19 are contained, and form pockets, between each of which pair of pockets is located a wall 24 having tapering and preferably arc-shaped surfaces 25, 26, as represented. The ribs 27 and 28, and the ribs 24 85 formed by the tapering walls of the pockets 22 and 23, preferably extend flush with the sides of the wheel, thereby affording a journal fit of the wheel at its circumference in the casing.

In the construction illustrated, the arrangement of the inlets for the motive fluid, which may be compressed air, steam, water, gas or the like, is as follows:

The fluid is adapted to be discharged 100 against the wheel from above and below through the inlets 13^a or 13^b in the casing, which extend tangentially of the wheel 17. These inlet-passages lead from bores 29, 29 provided in the wall of the casing 13 and 105 transversely thereof, each of the bores having journaled in it a valve in the form of a tube 30 provided with a longitudinal slit 31, a closed, squared end 32, and an open opposite end 33, the open ends of the tubes com- 110

2
municating with branch pipes 34 extending through a side of the casing 13 and united at their outer ends to a main pipe 35 through which a supply of fluid is introduced into the engine. The squared ends 32 of the valves have cranks 33^a fixed to them which are pivotally connected through the medium of links 34^a with the opposite ends of a rigid bar 35^a journaled on a sleeve 36 surrounding a journal bearing 37 carried by one side of the inner casing 13, a handle 38 being provided for turning the bar 35^a on its journal to turn the valves in the openings 29.

The operation of the device is as follows: Assuming the valves to be in the position illustrated in Fig. 1 in which the slits 31 of the valves are out of registration with the inlets 13^a and 13^b, to operate the engine, as for instance from left to right, the handle 38 is turned to the left, thereby causing the slits 31 of the valves to register with the inlets 13^b, whereupon the fluid entering the engine at x discharges through the inlets 13^b into impingement with the tapering walls 25 of the pockets 22, the impact-surfaces 21 and into the pockets 23, these impact-surfaces and pockets as they are brought into registration with the inlets 13^b being successively acted upon by the fluid as it leaves the inlets. The spent-fluid discharges from the grooves in the wheel through the openings 15 and thence between the inner and outer casings to the exhaust. The engine may be reversed by turning the handle 38 to the right to cause the slits in the valves to register with the inlets 13^a, whereupon the motive fluid impinges against the impact surfaces 20 and the tapering walls 26 of the pockets and forces itself into the pockets 22, and thus causes the wheel to rotate in the reverse direction.

The provision of the arc-shaped grooves 19, and other rounding surfaces as shown, presents a structure affording but slight resistance to the air, which, owing to the rapid rotation of the wheel 17, the periphery of the latter must encounter, and therefore the retarding effect of imprisoned air between the wheel 17 and the casing 13 is minimized.

The provision of the impact-surfaces 20 and 21, the impact-surfaces afforded by the tapering walls 25 and 26 of the pockets 22 and 23 and the oppositely disposed pockets,

affords a construction capable of great speed of rotation and of high power when running in either direction.

Another important feature of the engine is that of its capability of rapid reversal while running at maximum speed, this result being due to the formation of the periphery of the wheel in accordance with my invention.

While I have shown and described the member 17 as having grooves of a particular shape formed in it for affording impact-surfaces and pockets, I do not wish to be understood as limiting myself to the particular formation shown, as various modifications may be made without departing from the spirit of my invention.

What I claim as new, and desire to secure by Letters Patent, is—

1. In a turbine engine, a rotary member journaled therein and provided with a series of pairs of oppositely disposed pockets with a rib interposed between the pockets of each of said pairs and having tapering curved walls forming opposed impact-surfaces for receiving the impact of the motive fluid introduced into the engine.

2. In a turbine engine, a rotary member journaled therein and provided with a series of pairs of oppositely disposed pockets with a rib interposed between the pockets of each of said pairs, and a pair of oppositely extending impact-surfaces interposed between each pair of pockets, for the purpose set forth.

3. In a turbine engine, a rotary member journaled therein and provided with a series of pairs of oppositely disposed pockets with a pair of oppositely extending impact-surfaces interposed between each pair of pockets, for the purpose set forth.

4. In a turbine engine, a rotary member journaled therein and provided with a series of pairs of oppositely disposed pockets of curved shape in cross-section with a rib interposed between the pockets of each of said pairs and having tapering curved walls forming opposed impact-surfaces, and a pair of oppositely tapering curved impact-surfaces interposed between each pair of pockets, for the purpose set forth.

JOSEPH KADIERA.

In presence of—

RALPH A. SCHAEFER,
W. T. JONES.
